UNITED STATES PATENT OFFICE.

FINIS J. HENDERSON, OF MORELAND, ARKANSAS.

DOOR-CHECK.

1,296,184.

Specification of Letters Patent.

Patented Mar. 4, 1919.

Application filed July 31, 1918. Serial No. 247,661.

To all whom it may concern:

Be it known that I, FINIS J. HENDERSON, a citizen of the United States, residing at Moreland, in the county of Pope and State 5 of Arkansas, have invented certain new and useful Improvements in Door-Checks, of which the following is a specification.

This invention relates to door checks, and the object thereof is to construct a simple 10 and efficient device of this character which will effectively hold a door or gate in open position until released.

Another object is to provide a check of this character with means for releasably 15 holding the surface engaging member out of operative position when not desired for use.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made 20 within the scope of what is claimed without departing from the spirit of the invention.

In the accompanying drawings:—

Figure 1 represents an edge view of a portion of a door showing this improved check 30 applied, and in side elevation, the surface engaging member thereof being in operative position in full lines, and in inoperative position in dotted lines.

Fig. 2 is a front elevation of the check 35 tached,

Fig. 3 is a side elevation showing the check applied and in inoperative position, and

Fig. 4 is a detail perspective view of the 40 surface engaging member and its connecting parts.

In the embodiment illustrated the check constituting this invention is shown applied to a door D and comprises a plate 1 here 45 shown rectangular in form, although obviously it may be of any desired configuration. This plate 1 has a plurality of laterally projecting apertured ears 2 for connecting it to the outer face of the door or gate in connection with which it is to be used.

This plate 1 has its lower end rolled to form a bearing or knuckle 3 for hinged or pivotal connection with the plate of the surface engaging member 5. This member 5 is composed of a single piece of wire bent 55 into rectangular form with the cross bar 4 at

one end mounted in the bearing 3 and forming a journal for the member 5, while its other cross bar 4' is designed to be engaged by a spring catch presently to be described. 60 One side member of the member 5 is extended longitudinally at one end to form an arm 6 having a penetrating spur 7 at its free end, said spur being turned laterally and pointed to facilitate its engagement with the floor 65 or surface when the door or gate is to be held open by said device. The cross bar 4' has its free end looped to form an eye 4'' which encircles the side member of the surface engaging element 5 which carries arm 6. 70

The upper end of plate 1 is also rolled to form a bearing 15 in which is mounted a pintle 16 carrying thereon at its opposite ends beyond said bearing 15, apertured lugs 14 which project upward from one arm 8 75 of a latch 10. This latch 10 which is substantially L-shaped, the ears or lugs 14 of which are disposed adjacent the juncture of its arms, is designed for locking the member 5 in inoperative position. The arm 10' of 80 this latch is in the form of a plate overlying plate 1 and having an aperture in its free end through which extends a stud 11 which projects laterally from plate 1 and has a coiled spring 12 mounted thereon between 85 the outer face of arm 10' and a washer 13 secured to the outer end of the stud 11 by any suitable means, a nut 13' being here shown for this purpose. This spring 12 exerts its tension to normally force arm 10' flat 90 against the plate 1 and to hold arm 8 in normal locking position. This arm 8 has a downward offset 8' with its free end flared upwardly as shown at 9 to facilitate the passage thereunder of the cross bar 4' of the 95 locking or surface engaging element 5. This flared end 9 also is designed for engagement by the user to release said cross bar, the thumb of the user being placed thereunder and on swinging the member 10 on its pivot 16 the free end of its arm 10' will move outwardly against the tension of spring 12 and thus release the member 5 and permit it to be swung downwardly into the position shown in Fig. 1, whereby the penetrating spur 7 thereof will operate to lock the door D against movement. 100

When it is desired to release the member 5 from the floor or other surface, the door is moved inward a sufficient distance to permit the disengagement of the spur 7 with the floor, and the member 5 may then be 110

swung upwardly into the dotted line position shown in Fig. 1, the cross bar 4' snapping under the offset 8' in the arm 8 of the latch 10.

5 While this device has been shown and described as applied to a door, it may be obviously equally well applied to a gate or any other swinging object of this character.

10 The foregoing description and the drawings have reference to what may be considered the preferred or approved form of my invention. It is to be understood that I may make such changes in construction and arrangement and combination of parts, materials, dimensions, etc., as may prove expedient and fall within the scope of the 15 claimed invention.

Having thus fully described my invention, what I claim as new and desire to secure by 20 Letters Patent, is:—

1. A door check comprising a plate having attaching means, an L-shaped latch pivotally mounted on said plate at the junction of the arms, one of said arms of said latch 25 overlying said plate, a spring mounted to hold said arm normally in contact with said

plate, a surface engaging member pivotally mounted on said plate and having a lateral extension for releasable engagement by said latch to hold said swinging member in inoperative position. 30

2. A door check comprising a plate having its opposite ends rolled to form bearings and provided at its side edges with apertured attaching lugs, an L-shaped latch 35 having apertured ears for pivotal connection with the bearing at one end of said plate, one arm of said latch overlying said plate, a spring for yieldably holding said arm in operative position, a surface engaging element having a lateral extension mounted in the bearing at the other end of said plate, said element having another lateral extension for releasable engagement by said spring pressed catch whereby said element 40 is held in inoperative position.

In testimony whereof I affix my signature in presence of two witnesses:

FINIS J. HENDERSON.

Witnesses:
